(57) **CLAIM**

The ornamental design for a water closet, as shown and described.

DESCRIPTION

In a preferred embodiment, the nature of this product is as a plumbing fixture which is primarily useful for receiving the liquid and solid waste of humans.

FIG. 1 is a right, top, front perspective view of a water closet embodying my new design;

FIG. 2 is a right side elevational view thereof;

FIG. 3 is a left side elevational view thereof;

FIG. 4 is a front elevational view thereof;

FIG. 5 is a rear elevational view thereof;

FIG. 6 is a top plan view thereof; and,

FIG. 7 is a bottom plan view thereof.

The broken line representations of holes in FIGS. 1 and 6, of a flush handle in FIGS. 3-6, and of mounting structure and other support structure in FIG. 7, are for the purpose of illustration only, and form no part of the claimed design.
